UNITED STATES PATENT OFFICE.

FREDRICK CARTER, OF STE. AGATHE DES MONTES, QUEBEC, CANADA.

DYEING-MACHINE.

1,400,417.

Specification of Letters Patent.

Patented Dec. 13, 1921.

Application filed February 23, 1921. Serial No. 447,352.

To all whom it may concern:

Be it known that I, FREDRICK CARTER, a subject of the King of Great Britain, residing at Ste. Agathe des Monts, in the 5 Province of Quebec and Dominion of Canada, have invented new and useful Improvements in Dyeing-Machines, of which the following is a specification.

This invention relates to improvements in 10 dyeing machines and aims to provide means whereby the material to be dyed may be guided through a dye tank in a continuous manner.

The invention is especially adapted for 15 use in connection with sewing machines, the primary object being to provide means for supporting a spool of thread and guiding the latter through a tank of dye as it is unwound from the spool, so that the thread 20 may be fed to the sewing machine in any desired color.

Another object is the provision of a novel form of guide, which is so mounted as to permit of its use in connection with any one 25 of a number of dye tanks, so that a change of color of the thread may be made without changing the spool.

Other objects and advantages of the invention will appear as the following description 30 is read in connection with the accompanying drawings.

In the drawings:—

Figure 1 is a side elevation of a dyeing machine constructed in accordance with the 35 present invention.

Fig. 2 is a plan view of the same.

Fig. 3 is a longitudinal sectional view of the same.

Fig. 4 is a cross section.

Fig. 5 is a view similar to Fig. 4 but showing the cover of the casing partly raised to illustrate the manner of changing the position 40 of the thread guides.

Referring to the drawings in detail, 45 wherein like characters of reference denote corresponding parts, the invention includes a casing 10 of box-like formation, the front 11 of which is hinged to the bottom 12 by hinges 13. The casing is also provided with 50 a top 14 hinged along one edge, as shown at 15. This permits of the receptacle being opened for the purpose of obtaining access to the interior which is adapted to contain a number of dye tanks 16.

55 The cover 14 is provided with a flange 17 along one edge, which is adapted to take

over the front wall 11, so as to hold the latter in closed position. The said cover is also provided with a longitudinally extending slot 18, the edges of which provide a guide 60 for a slide 19, which is capable of movement longitudinally of the slot. This slide has secured thereto a standard 20, the upper end of which is provided with a cross arm 21. Located at the opposite end of the cross arm 65 21 is an eye 22, the lower end of the standard 20 carrying a similar eye 23.

The eyes 22 and 23 are designed for the purpose of guiding a thread 24 which may be unwound from a reel or spool 25, which is 70 supported upon an arbor 26, the latter being mounted in standards 27, located at the end of the casing 10. The opposite end of the casing has a guide arm 28 through which the thread is passed.

In the use of the invention, the receptacle is adapted to be in convenient position so that the thread after leaving the guide 28 may be threaded through the sewing machine. The standard 30 which forms a guide 80 for the thread may be positioned so as to have its lower end extend within the tank 16, which contains the desired color. As the machine is operated, the thread will be passed through the guide, thereby changing 85 it to the color required for use. The color of the thread may be changed without changing the spool by raising the cover to the position shown in Fig. 5 and moving the slide 19 to properly position the standard 20 in 90 the desired tank 16. With the form of guiding means shown for passing the thread through the dye, the said thread is quickly dried, the eye 22 which receives the thread after it leaves the tank, acting to squeeze or 95 wring the moisture therefrom.

The invention is susceptible of various changes in its form, proportions and minor details of construction and the right is herein reserved to make such changes as properly fall within the scope of the appended claims.

Having described the invention what is claimed is:—

1. A dyeing machine comprising a receptacle, a T-shaped member supported above and extending into the receptacle and guides positioned at each end of the T-shaped member, whereby the material to be dyed may be guided through said receptacle. 105

2. A dyeing machine comprising a plurality of receptacles and material guiding

- means supported above the latter and means whereby the guiding means may be adjustably positioned to extend into any one of the receptacles.
5. 3. A dyeing machine comprising a casing, dye tanks located therein, material guiding means and means supported by the casing for positioning the fabric guiding means into any one of the tanks.
10. 4. A dyeing machine comprising a casing, a slotted cover therefor, dye tanks located within the casing and a material guide ex-
- tending through and adjustable along the slot in the cover for guiding the material through any one of the tanks. 15
5. A dyeing machine comprising a casing, a slotted cover therefor, dye tanks located within the casing, a reel supported at one end of the casing and means adjustably mounted upon the casing, whereby the contents of the reel may be guided through any one of the dye tanks. 20

In testimony whereof I affix my signature.
FREDRICK CARTER.
